DESIGN FOR A PHOTOGRAPHIC FILM DEVELOPING UNIT OR SIMILAR ARTICLE

Douglas F. Winnek, Margate City, N. J.

Application December 17, 1946, Serial No. 135,579

Term of patent 14 years

(Cl. D61—1)

To all whom it may concern:

Be it known that I, Douglas F. Winnek, a citizen of the United States of America, residing at Margate City, in the county of Atlantic and State of New Jersey, have invented a new, original, and ornamental Design for a Photographic Film Developing Unit or Similar Article, of which the following is a specification, reference being had to the accompanying drawing, forming a part thereof, wherein:

Fig. 1 is a perspective view of the front and side of a photograph film developing unit or similar article, showing my design; and

Fig. 2 is a perspective view of the rear and opposite side of the unit of my design.

I claim:

The ornamental design for a photographic film developing unit or similar article, substantially as shown.

DOUGLAS F. WINNEK.
